UNITED STATES PATENT OFFICE.

MAGNUS KRISTOFFERSSON, OF LIMHAMM, SWEDEN.

FOAM-DESTROYING DEVICE.

Application filed March 24, 1926, Serial No. 97,134, and in Sweden March 28, 1925.

My invention relates to a foam-destroying device especially adapted to be used in dairies for reducing foam accompanying the skimmed milk from the separators into liquid, although the apparatus may be used 5 also for other similar purposes.

According to the present invention a rotary impeller or vane wheel is used in the same way as hitherto has been the case but 10 the new wheel is given a peculiar shape resulting in an improved mode of operation and a substantially increased effectiveness.

By way of example an embodiment of the invention is illustrated in the accompanying 15 drawing in which:

Fig. 1 is an elevation of the foam-destroying device.

Fig. 2 is an elevation perpendicular to Fig. 1.

Fig. 3 is a horizontal cross sectional view 20 through the vane wheel.

A suitable frame 1 forms bearings and housing for a worm gear in which the shaft of the worm wheel outside the housing carries a fast and loose pulley or the like by 25 means of which it is put into rotation, and the worm is carried by a vertical shaft 2 carrying the vane wheel 3 at its lower end. This mode of driving mechanism is only 30 shown by way of example and comprises no essential part of the present invention. The frame 1 is placed on top of a receptacle 4 in which the foam is to be destroyed, the vane wheel being contained in said receptacle.

According to the form shown the vane wheel is provided with four radial vanes each consisting of a plate or metal sheet 5 the lower and outer edges of which are bent 40 forwards in the direction of rotation of the wheel in such a way that each vane has the shape of a cup or the like. As shown in the drawing the outer edge 6 is bent forwards substantially at a right angle to the sheet 5, while the lower edge 7 is not bent abruptly but rounded as shown in Figs. 1 and 2. This shape of the edges or the side walls of 45 the vanes, however, may vary within certain limits, and the lower side wall of the cup or the bent lower edge of the sheet may 50 also be wholly dispensed with, if for instance the vane or the sheet is placed in a somewhat slanting position in such a way that the lower edge of the vane or sheet is the forward one in the direction of rotation. The vanes are preferably fastened to the

under side of a disc 9 carried by the lower end of the shaft 2, though they also may be fastened to or carried by the shaft in any other way. The whole vane wheel may in 60 the form shown be formed in a very simple manner by only two pieces of sheet, but the construction or joining together of the vane wheel per se is not an essential part of the invention and may be varied in different 65 ways.

In the angle between the outer wall or the edge portion 6 and the bottom of the cup or the plane main portion 5 of the sheet in each vane a narrow slot or opening 8 is provided which is of a great importance for 70 the invention as will be understood by the following description of the mode of action of the apparatus.

At the rotation of the vane wheel the 75 foam floating on top of the liquid in the receptacle 4 is caught by the cup shaped vanes 5 in which said foam acted upon by the centrifugal force is moved radially outwards 80 along the bottom of the cup and compressed against the outer wall 6, whereafter it is pressed out through the narrow slot 8, simultaneously being reduced to liquid. For obtaining this result it is important to keep the slot 8 as narrow as possible, so that all 85 air-bubbles in the foam are positively torn asunder when they are pressed out through the same. When sufficiently narrow or correctly dimensioned slots are used the action 90 will be extraordinarily effective, and the efficiency of the device is much greater than in any hitherto known foam-destroying device provided with vane wheel. By means 95 of a comparatively small vane wheel and an inconsiderable consumption of power much larger quantities of foam can be destroyed during a certain time than hitherto.

The mode of operation and the great efficiency of the new foam-destroying device 100 involve the advantage that the whole apparatus may be carried out in such small a size that it becomes easily portable and can be moved and applied to any milk receptacle. The vessel in which the apparatus is used ought, of course, to be arranged in such a 105 manner that the foam floating on top of the liquid, which for instance is supplied to the vessel continually, will not be in a position to leave the vessel, until it has been condensed. In the apparatus shown in the drawing the 110 outlet 10 from the vessel 4 is placed in the side of the vessel at some distance above the

bottom in such a way that a suitable level of the liquid may be maintained, and this outlet is connected with a pipe 11 reaching to the bottom of the vessel in order to prevent the foam from escaping through the outlet.

It is not necessary that the vane wheel is immersed in the foam to be destroyed, as the wheel sucks in the foam.

Another advantage of the new apparatus is that it can be cleaned very easily, as all its surfaces are easily accessible.

What I claim is:

1. A foam-destroying device comprising a vane wheel having cup shaped vanes provided with a narrow slot at their outer wall through which slot the foam caught by the vane and thrown outwards by the centrifugal force is pressed out after having been compressed against said outer wall.
2. A foam-destroying device comprising a vane wheel having cup shaped vanes consisting of plane radially arranged plates parallel to the shaft of the vane wheel, the outer edges of said plates being bent in a right angle in the direction of rotation and a narrow slot being provided in said angle.
3. A foam-destroying device comprising a vane wheel having cup shaped vanes pro-

vided with a narrow slot at their outer wall through which slot the foam caught by the vane and thrown outwards by the centrifugal force is pressed out, the vanes consisting of radially arranged plates parallel to the shaft of the vane wheel and at their lower edge bent forwards in the direction of rotation.

4. A foam-destroying device comprising a vane wheel having cup shaped vanes provided with a narrow slot at their outer wall through which slot the foam caught by the vane and thrown outwards by the centrifugal force is pressed out, said vanes being fastened to the under side of a disc carried by the vertical shaft of the vane wheel.

5. A foam-destroying device comprising a vane wheel having cup shaped vanes provided with a narrow slot at their outer wall through which slot the foam caught by the vane and thrown outwards by the centrifugal force is pressed out, the vane wheel and its driving gear being mounted on and carried by a common portable frame.

In testimony whereof, I have signed my name to this specification.

MAGNUS KRISTOFFERSSON.
